UNITED STATES PATENT OFFICE.

EUGENE D. FERRELL, OF WAYZATA, MINNESOTA.

HYDROVAPORIZER.

1,303,187.

Specification of Letters Patent. Patented May 6, 1919.

Application filed July 12, 1916. Serial No. 108,868.

To all whom it may concern:

Be it known that I, EUGENE D. FERRELL, a citizen of the United States, residing at Wayzata, in the county of Hennepin and

5 State of Minnesota, have invented certain new and useful Improvements in Hydrovaporizers; and I do hereby declare the following to be a full, clear, and exact description of the invention, such as will enable 10 others skilled in the art to which it appertains to make and use the same.

My invention has for its object to provide an extremely simple and efficient device for introducing a spray of water into the explosion chambers of internal combustion engines. This device, because of the function it performs, I have called a hydrovaporizer.

It is a well known fact that the introduction of water vapor with the explosive charge into the explosion chamber of an explosive engine increases the efficiency of the engine and assists lubrication. A device of this kind will increase the efficiency of an internal combustion engine under almost all, or nearly all atmospheric conditions, but is especially desirable when the air is hot and dry.

The improved hydrovaporizer, in its preferred form and arrangement, is illustrated in the accompanying drawings wherein like characters indicate like parts throughout the several views.

Referring to the drawings:

35 Figure 1 is a side elevation showing the hydrovaporizer applied to an explosive engine of the well known Ford type;

Fig. 2 is a side elevation of the hydrovaporizer;

40 Fig. 3 is a horizontal section on the line 3—3 of Fig. 2; and

Fig. 4 is a vertical section on the line 4—4 of Fig. 3.

The water jacketed cylinder casting of the 45 engine is indicated, as an entirety, by the numeral 5. The numeral 6 indicates a hot water outlet tube from the water jackets of the several cylinders. The numeral 7 indicates the carburetor and the numeral 8 the 50 manifold that leads from the carburetor to the explosion chambers of the several cylinders of the engine.

The water for supplying the water vapor may be taken from any suitable source, but is 55 preferably taken from the water circulating system of the engine, so that there will be a

supply of hot water which will make vaporization an easier matter.

The hydrovaporizer comprises a casing 9 having a chamber containing a filtering material 10, such as coarse sand or crushed silica, for example. One side of the chamber containing this filtering material 10 is provided with a tubular delivery nipple 11 that is screw-threaded into the intake manifold 8. 60 At one side, the casing 9 is provided with a vertically extended valve chamber 12 that is connected to the chamber containing the filtering material 10 by a port 13. This port 13 is adapted to be opened and closed, at 70 will, by an oscillatory cut-off valve 14 provided at one end with an arm 15 connected to an operating rod 16. This operating rod 16 extends through a guide tube 17 shown as supported at one end directly from a head 75 18 that is detachably secured to the outer side of the chamber containing the filtering material 10. The rod 16 will usually be extended through the instrument board of the automobile, so that the valve 14 may be operated from the driver's seat.

The valve chamber 12, at its lower end, has an air intake port 19 that is normally closed by a check valve 20, as shown, of the ball type. Screwed into the upper end of 85 the said valve seat 12 is a reducing tube 21, the lower portion of which has a port 22 normally closed by a check valve 23, as shown, of the ball type. A small stem 24 connects the two check valves 20 and 23 so that when 90 the former is raised, the latter will also be raised. Normally, both of the said check valves will be seated.

The numeral 25 indicates a small water supply pipe which leads from the water 95 jacket of the cylinder casting, preferably from the outlet tube 6 thereof, and is connected to the upper end of the reducing tube 21, by a suitable coupling 26, best shown in Fig. 4.

100 Spraying of water requires circulation of air in contact with the water to be sprayed, and this is provided for in the device above described. When the cut-off valve 14 is closed, there will, of course, be no supply of 105 vapor. By opening the said valve 14, more or less quantity of vapor supplied may be regulated.

A fine meshed screen 10^a is placed in the filtering chamber adjacent to its delivery 110 nipple 11. This screen holds the filtering material in place, and it is of such fine mesh

that water will not flow therethrough by gravity but will be delivered therethrough in the form of a fine spray under the action of the suction produced from the engine.

- 5 When the said valve 14 is opened, the water vaporizing action will be as follows:

Under each suction stroke of the engine, and simultaneously with the intake of the hydrocarbon vapor from the carburetor, the 10 suction produced in the valve chamber 12, acting on the relatively large check valve 20, will simultaneously raise the two valves 20 and 23, thereby simultaneously opening the air port 19 and water port 23. When the 15 said port 22 is opened, water will flow downward into the said chamber 12, and come into contact with the air taken in through the port 19, will be taken up, thereby and vaporized. Vaporization will further be 20 produced in passing through the so-called filtering material 10. The said filtering material, while desirable, is not in all cases necessary.

Obviously, the water vapor thus introduced into the manifold 8 will be commingled with the explosive charge; and when the explosion takes place in the engine, will be converted into steam, which, in itself, not only assists in lubrication, but increases in ef-

fective force of the explosion, probably, in 30 several different ways, but certainly to the extent that it tends to prolong the pressure impulses produced by the explosion.

The device may be cheaply constructed and easily applied to any and all explosive 35 or internal combustion engines.

What I claim is:

A hydrovaporizer for explosive engines comprising a casing provided with a discharge port and having axially spaced air 43 and water intake ports delivering the air and water, respectively, inward from opposite directions, valves normally closing said air and water intake ports, said air valve having greater area than said water 45 valve, an axial connection between said two valves whereby, under the action of suction on said air valve, both valves will be positively and simultaneously opened, and a cut-off valve for simultaneously cutting said air 50 and water valves out of action.

In testimony whereof I affix my signature in presence of two witnesses.

EUGENE D. FERRELL.
